United States Patent

Des. 237,371
Patented Oct. 28, 1975

237,371

LIFT TRUCK BODY

Warner Kent Brown, Battle Creek, Mich., assignor to
Clark Equipment Company

Filed Oct. 15, 1973, Ser. No. 406,733

Term of patent 14 years

Int. Cl. D12—05

U.S. Cl. D12—61

FIG. 1 is a right side elevational view of a lift truck body showing my new design;

FIG. 2 is a left side elevational view thereof;

FIG. 3 is a left front perspective view thereof; and

FIG. 4 is a top rear perspective view thereof.

The portions shown in broken lines in the drawing are for illustrative purposes only.

I claim:

The ornamental design of a lift truck body, as shown and described.
